CRAWLING TRAINER FOR INFANTS

Allen B. Cherry, Oklahoma City, Okla., assignor to W. O. Gifford, Bartlesville, Okla., and Alvin Smith, Dewey, Okla., jointly

Filed Feb. 6, 1968, Ser. No. 10,462

Term of patent 14 years

U.S. Cl. D25—1
Int. Cl. D12—13

FIG. 1 is a perspective view of the crawling trainer for infants embodying my design;

FIG. 2 is a view of the top of the crawling trainer for infants shown in FIGURE 1;

FIG. 3 is a view of the end of the crawling trainer for infants shown in FIGURE 1;

FIG. 4 is a sectional view of the crawling trainer for infants shown in FIGURE 1.

I claim:

The ornamental design for a crawling trainer for infants, as shown.
